UNITED STATES PATENT OFFICE

2,349,123

STEAM INJECTOR

Walter Howard Tinker, Boston, Mass.

Application June 18, 1942, Serial No. 447,579

17 Claims. (Cl. 103—265)

This invention relates to a steam injector and is a development of the injector forming the subject matter of my copending application for Patent Serial No. 431,313, filed February 17, 1942, patented Dec. 21, 1943, No. 2,337,283.

In said application for patent I have disclosed a steam injector in which the live steam valve and the water valve are so connected as to open together to the full limit of their respective ranges of opening movement by a single movement of the operating lever, the water valve opening at a faster rate than the live steam valve to assure an adequate supply of water at the point of entrainment when starting, this being a condition essential to reliable starting of the injector, to prevent steam solely from filling the venturi to the exclusion of water. The invention of said pending application also provided that the full open areas of both valves is reached before they reach their limits of movement in an opening direction so that they have a range of movement within their full open capacity phase, and that in the case of the water valve it passes a throttling constriction within its full open capacity phase, so quickly in its opening movement at starting that the throttling effect is negligible, but when both valves are in their full open capacity phase beyond said constriction, the operating lever may be slowly manipulated to move said valves in a closing direction, the water valve moving toward said constriction and its capacity being throttled thereby, while the live steam valve remains open at full capacity.

Thus, by the operation of a single lever the injector may be started and the ratio of water supply to live steam be subsequently regulated according to boiler demands.

Said application for patent also discloses means by which exhaust steam from the engine, when present, acts through an auxiliary venturi to heat the water supplied to the entraining nozzle of the main venturi, which water being heated and already under some pressure and motion when it enters the main venturi, improves the efficiency of the injector. It is to be noted, however, that in the device of the said application for patent the water from the water valve, whether or not exhaust steam be present, always passes through the auxiliary venturi, creating a situation of inflexibility which is not always optimum for the conditions of operation of the injector.

Said application for patent also provides non-automatic means operable at will, for holding the

overflow valve of the main injector chamber closed under certain operating conditions in which a pressure greater than atmospheric develops in said chamber.

5. The subject invention is an improvement over that of said application for patent, having for one of its objects to provide a steam injector of the general type disclosed in said application for patent in which the water chamber supplied by
10. the water valve is branched into two paths of flow which terminate in separate entraining nozzles at the live steam venturi, one of which paths includes the auxiliary venturi into which water is entrained by exhaust steam and delivered to the associated entraining nozzle of the live steam venturi under constant conditions of temperature and pressure within limits, under a given pressure of exhaust steam, the other path being outside of said auxiliary venturi and
15. delivering water to its entraining nozzle of the live steam venturi when there is no exhaust steam present, and the auxiliary venturi is consequently inactive, when the water supply admitted through the water valve is greater than the capacity of the auxiliary venturi entraining nozzle, and when the exhaust steam pressure is so great as to force water through the spillways of the auxiliary venturi.
20. Another object of the invention is to provide a steam injector having a divided water chamber as described, in which the water valve has a throttling range the minimum capacity of which is sufficient to supply the entraining nozzle of the auxiliary venturi when exhaust steam is present in said auxiliary venturi, whereby said auxiliary venturi delivers water at constant temperature and pressure to said live steam venturi throughout the throttling range of said water valve, excess water above said minimum being
25. delivered to said live steam nozzle through a path which by-passes the auxiliary venturi without interfering with the constancy of the operation of said venturi.

30. 35. 40. 45. 50.
- Another object of the invention is to provide an injector of the type described, in which the water valve delivers into an ante-chamber from which two lateral branches debouch, each leading to a separate entraining nozzle in the live steam venturi, one branch being an exhaust steam venturi communicating with said ante-chamber at the mouth of its exhaust steam entraining nozzle, the other branch being an outer chamber surrounding said exhaust steam venturi beyond the mouth of said entraining nozzle, the

- 55.

latter having spillways communicating with said outer chamber, said ante-chamber communicating with said outer chamber above the level of the mouth of said exhaust steam entraining nozzle whereby the mouth of said entraining nozzle is first inundated by water supplied to said ante-chamber, the excess then overflowing into said outer chamber and to the associated entraining nozzle in the main venturi.

A further object of the invention is to provide an injector of the type described, in which the auxiliary venturi when operating under exhaust steam is cooled by heat exchange with excess water overflowing into said outer chamber and over the surface of said auxiliary venturi in the mixing region.

Still another object of the invention is to provide in an injector of the type described, in which exhaust steam under excess pressure in the auxiliary venturi causes steam and water mixture to issue from the spillways of the auxiliary venturi, heating the water which passes through the outer chamber to the main venturi.

Another object of the invention is to provide the overflow chamber which surrounds the spillways of the main venturi with a fluid pressure closed relief valve, and to connect the closing means of said valve to the pressure end of the auxiliary venturi so that when the exhaust steam is assisting the injector, this being a condition under which superatmospheric pressure may exist in the overflow chamber of the main venturi, the pressure developed by the auxiliary venturi will hold the relief valve closed, while at other times, and usefully at starting the injector, this valve closing pressure will be absent and the relief valve free to open to permit overflow from said overflow chamber.

A further object of the invention is to provide the auxiliary venturi with a forcing nozzle and a water entraining nozzle in communication with an exhaust steam admitting nozzle, a cut-off valve intervening which is opened under pressure of the exhaust steam, the opening means being connected to said exhaust steam admission nozzle, and a cross-sectional area of said exhaust steam admission nozzle being greater than the combined cross-sectional areas of said auxiliary venturi forcing and entraining nozzles whereby a dominant steam pressure is maintained in said steam admission nozzle, holding said cut-off valve open while ever there is sufficient exhaust steam present to operate said auxiliary venturi.

Other objects of the invention will appear as the following description of a preferred and practical embodiment thereof proceeds.

In the drawings which accompany and form a part of the following specification and throughout the several figures of which the same characters of reference have been employed to designate identical parts:

Figure 1 is a side sectional view through an injector, embodying the principles of the subject invention;

Figure 2 is a vertical cross-section taken along the line 2—2 of Figure 1, the lower portion being omitted;

Figure 3 is a cross-section taken along the line 3—3 of Figure 1;

Figure 4 is a cross-section taken along the line 4—4 of Figure 1;

Figure 5 is a cross-section taken along the line 5—5 of Figure 1;

Figure 6 is a fragmentary side sectional view through a modified form of injector.

Referring now in detail to the several figures, the numeral 1 represents the injector as a whole 5 which comprises a casing 2 surrounding the main or live steam venturi 3 forming the overflow chamber 4 provided with the outwardly opening relief valve 5 which permits the discharge of water and steam through the outlet

10 6. The live steam venturi 3 is served by a live steam valve 7 controlling the live steam admission conduit 8. Said valve, when opened, admits live steam to the forcing nozzle 9 and the entraining nozzles 10 and 11 which are serially 15 arranged about the forcing nozzle, the entraining nozzle 11 receiving steam from the entraining nozzle 10.

Said entraining nozzles are secured in partition walls 12 and 13, respectively, formed in 20 the casing 2, and which define separate water chambers 14 and 15 surrounding the mouths of the respective entraining nozzles.

The live steam venturi has the usual downwardly convergent velocity building sections 16, 25 17 and 18, and the usual downwardly convergent pressure building section 19. Spillways 20, 21 and 22 open from the live steam venturi into the overflow chamber 4. A pressure cap 23 closes the lower end of the casing 2, encompassing the 30 pressure building section of the venturi, forming a water chamber 24, which is adapted to be connected to the boiler at the outlet 25.

The relief valve 5 has a stem 26 which functions as a piston working in the cylinder 27, 35 said cylinder being in communication with the water chamber 14 by means of a tube 28. It will be presently explained that when pressure is developed in the chamber 14 the relief valve will be held closed.

40 The upper portion of the casing 2 has a lateral inlet 29 registering with an outlet opening 30 in a hollow fitting which in general is designated by the reference character 31, said fitting being bolted in water tight relation to the casing 2. Said fitting is formed with a substantially horizontal partition 32 extending transversely thereacross, as shown in Figures 3 and 5, having an upturned forward end 33 with a threaded bore 34 receiving and supporting the anterior section 50 35 of the auxiliary venturi 36.

Said partition 32, together with the upturned end 33 and the top wall of the fitting 31 forms a water chamber 37 through which the auxiliary venturi 36 longitudinally extends, the inner or 55 pressure building section 47 of said venturi being screwed into a bore in the casing 2 and supported thereby in spaced relation to the walls of the fitting 31.

A water entraining nozzle 38 is screwed into the forward end of the fitting 31 having its inner end in entraining relation to the mouth of the auxiliary venturi. An exhaust steam forcing nozzle 39 passes through the entraining nozzle concentrically thereto having its inner end terminating within the anterior section 35 of the auxiliary venturi. The concentric inlets of the forcing nozzle 39 and entraining nozzle 38 terminate in a plane across which passes the adjacent face 40 of an exhaust steam opening gate valve 41. The valve 41 establishes communication between an exhaust steam inlet 45 and the entraining and forcing nozzles of the auxiliary venturi.

A water valve 42 controls communication between a water inlet 43 coming from a suitable

source of supply and a water chamber 44 in the fitting 31 below the partition 32 hereinafter for convenience referred to as an ante-chamber, inasmuch as water first enters it from the valve 42 and then passes through the auxiliary venturi 36 or through the surrounding water chamber 37 according to operating conditions. When the valve 40 is open and exhaust steam is operating through the auxiliary venturi 36. Water from the anti-chamber 44 is entrained at the mouth 46 of the entraining nozzle, passing through the auxiliary venturi with the exhaust steam, being warmed by said steam, building up pressure in the pressure building section 47 of said venturi which communicates with the water chamber 14 of the main venturi to the exclusion of the outer or surrounding chamber 37. This water heated by the exhaust steam and already in motion, enters at the mouth of the entraining nozzle 10.

Any water admitted by the water valve 42 in excess of the capacity of the entraining nozzle 38 of the auxiliary venturi rises above the level of the dam 48 constituted by the upper edge of the upwardly turned end 33 of the partition 32 and gravitates into the chamber 37 flowing over the outer walls of the auxiliary venturi in the mixing region. The floor of the chamber 37 constituted by the upper face of the partition 32 is substantially flush with the bottom of the outlet opening 30 so that water from said chamber 37 gravitates through said opening into the water chamber 15 with which the water chamber 37 exclusively communicates.

Also, at times when there is an excessive back pressure of exhaust steam, the water and steam mixture is forced through the spillways 49 which open from the auxiliary venturi into the surrounding chamber 37, this water also gravitating into the water chamber 15. The latter chamber surrounds the mouth of the entraining nozzle 11.

The water valve 42 is similar in construction to that shown in my aforementioned copending application, in that it is provided with a disk 50 above the valve 42 proper, which disk is small enough to pass through the opening in the valve seat 51 with clearance, and in conjunction with the periphery of said valve seat, has a throttling function in certain positions of the water valve.

In the illustrated embodiment of the invention the water inlet 43 is connected to a downward extension 52 below the valve seat 51, and being closed by a suitable cap 53. The depth of the extension 52 is sufficiently great to enable the water valve 42, together with the disk 50, to operate within said extension when being employed as a throttle valve. When the injector is not being operated, the water valve 42 has the position shown in the drawings, with the disk 50 in the ante-chamber. In starting, the water valve is moved swiftly from its closed position, as shown, to its lowermost position within the extension 52, assuming its maximum area of opening when the seat 51 is in a middle position between the valve 42 and the disk 50. The disk 50, however, passes the valve seat 51 so fast that its throttling effect during the starting movement is negligible, due to the water capacity of the ante-chamber and the branches constituted by the chamber 37 and the auxiliary venturi.

When the water valve 42, together with the disk 50, is within the extension 52, it may be slowly moved in a direction to bring the disk 50 toward or away from the valve seat 51 and thus throttle the amount of water admitted to the

ante-chamber 44. The relation of the disk 50 to the opening through the valve seat 51 should preferably be such that when the valve is in minimum throttling position sufficient water will be supplied to keep the mouth of the entraining nozzle 38 inundated while exhaust steam is operating the auxiliary venturi. Any excess of water admitted by the water valve will flow over the dam 48 into the chamber 37, chamber 15 and the entraining nozzle 11 without interfering with operation of the auxiliary venturi. Thus, under any constant head of exhaust steam the auxiliary venturi will deliver a constant volume of water at constant temperature to the entraining nozzle 10 of the main venturi throughout the entire throttling range of the water valve 42, thus enhancing the efficiency of the injector.

If there is no exhaust steam operating the auxiliary venturi, the amount of water which will enter at the mouth of the entraining nozzle 38 is negligible. Substantially all of the water admitted by the water valve will rise above the dam 48 and be presented to the main venturi at the mouth of the entraining nozzle 11.

It is a well-known fact that an injector will work better under low temperature conditions in the mixing region. Therefore, when the auxiliary venturi is being operated by exhaust steam and excess water is flowing over the dam 48 upon the outer surface of the auxiliary injector in the mixing region, the walls of the venturi will be cooled and greater efficiency obtained. The excess water will be correspondingly heated and be delivered to the entraining nozzle of the main venturi in heated state. Under excess exhaust steam pressure the low grade steam issuing from the spillways 49 will heat the water in the chamber 37, going to the entraining nozzle 11 of the main venturi.

The exhaust steam valve 41 is opened by exhaust steam which passes from the inlet 45 through the clearances between the valve 41 and its guides 54 shown in Figure 4, and through the clearance space 55 between said valve and the stem 56 which connects it to the plunger 57. The steam thus enters the plunger chamber 58 and moves the plunger 57 upward in the plunger cylinder 59, lifting the exhaust steam valve so as to establish communication between the exhaust steam inlet 45 and the forcing and entraining nozzles of the auxiliary venturi through the ports 60 of said valve. The cross-sectional area of the steam inlet 45 is made larger than the combined cross-sectional areas of the inlet ends of the forcing and entraining nozzles 39 and 38, respectively, so that there is always a dominant exhaust steam pressure in the inlet 45, ensuring that the exhaust steam valve 41 will be held open while ever there is enough exhaust steam present to operate the auxiliary venturi.

When the auxiliary venturi 36 is operating delivering water under pressure to the main venturi at the entraining nozzle 10, the pressure developed in the chamber 14 is communicated through the tube 28 to the overflow valve 5, holding it shut. It is only when the exhaust steam is assisting the operation of the injector that pressure may develop in the overflow chamber 4 which it is desirable should be retained. At starting, when there is no pressure in the chamber 14, the overflow valve is free to open to permit the venting of water and steam from the overflow chamber.

The hook-up of the water and steam valves in this injector is the same in principle as that

disclosed in my hereinbefore mentioned pending application, only the mechanical connections being somewhat different. The operating lever is indicated at 61. This is connected to a rocking lever 62 pivotally connected at an intermediate point to the swinging link 63, the latter being pivotally mounted on the fitting 2. The stem 64 of the live steam valve and the stem 65 of the water valve are connected to the rocking lever 62 on opposite sides of its axis of oscillation so that when the steam valve opens upwardly the water valve opens downwardly. The distances of the points of connection of the stems of said live steam valve and water valve from the axis of oscillation of the rocking lever 62 are so located that the water valve opens at a faster rate than the steam valve, for reasons fully set forth in my said pending application.

Means for holding the exhaust steam valve 41 shut when the injector is not operating, are provided in the form of a rocking lever 66 connected at one end to the rod 67 which forms a stop for the exhaust steam valve and at the other end having a pin and slot connection with the water valve stem 65. The rocking lever 66 is pivotally supported at an intermediate point by the swinging lever 69, said swinging lever 69 being pivotally mounted upon the fitting 31.

When the live steam valve and water valve are closed the end of the rod 67 lies adjacent the upper end of the stem 56 of the exhaust steam valve and prevents it from opening. For starting, the operator pulls the lever 61 upwardly, opening the live steam valve 7 and the water valve 42 to the full limits of their range of movement, at the same time withdrawing the rod 67 so that if there is exhaust steam present, it will open the steam valve 41. Throttling is accomplished by moving the lever 61 up or down by small increments while the water valve is in the extension 52 and the disk 50 below the plane of the valve seat 51.

Referring now to a modification of the injector, this may be similar in construction to the injector shown in Figure 1, with the exception that the starting of the auxiliary venturi 36 is facilitated by the provision of an overflow chamber with which certain spillways of the auxiliary venturi communicate, and a relief valve for said overflow chamber.

Figure 6 illustrates this variation in structure, the fitting 31 being formed with a wall 70, encompassing the spillways 49a and 49b, and defining with the conduit 71 an overflow chamber having the relief valve 72. It is preferred to have some of the spillways, for example the spillway 49, open into the water chamber 37, which leads to the entraining nozzle 11 of the main venturi.

While I have in the above description disclosed what I believe to be a preferred and practical embodiment of my invention, it will be understood to those skilled in the art that the specific details of construction and arrangement of parts as shown, are by way of example and not to be construed as limiting the scope of the invention as defined by the appended claims.

What I claim as my invention is:

1. Steam injector comprising a main venturi having live steam jet producing means at its anterior end and water entraining means operatively related to said steam jet producing means, a conduit from a water supply leading directly to said entraining means, a branch conduit from said water supply to said main Venturi entraining means comprising an auxiliary venturi hav-

ing exhaust steam jet producing means at its anterior end and a pressure nozzle at its posterior end communicating directly with said main Venturi entraining means, said nozzle venturi having water entraining means operatively related to said exhaust steam jet producing means in communication with said conduit, whereby, when exhaust steam is operating said auxiliary venturi, the latter by-passes a portion of the water from said water supply to said main venturi to the extent of the capacity of said auxiliary Venturi entraining means, at constant volume, temperature and pressure for a given head of exhaust steam.

5 2. Steam injector as claimed in claim 1, including a throttle valve in said water supply conduit interior to the point of communication of said auxiliary Venturi entraining means with said conduit having a minimum capacity not less than the capacity of said auxiliary Venturi entraining means, whereby variations in the volume of water admitted by said throttle valve affect the volume of water supplied direct to said main venturi by said conduit without disturbing the constant conditions of flow, temperature and pressure of water supplied by said auxiliary venturi.

10 3. Steam injector as claimed in claim 1, the entraining means of said main venturi comprising a pair of entraining nozzles serially related with respect to said live steam jet producing means, with which nozzles said conduit and said auxiliary venturi respectively communicate, said injector including a throttle valve in said water supply conduit interior to the point of communication of said auxiliary Venturi entraining means with said conduit having a minimum capacity not less than the capacity of the auxiliary Venturi entraining means, whereby variations in the 15 volume of water admitted by said throttle valve affect the volume of water supplied direct to said main venturi by said conduit without disturbing the constant conditions of flow, temperature and pressure of water supplied by said auxiliary venturi.

20 4. Steam injector as claimed in claim 1, the entraining means of said main venturi comprising a pair of entraining nozzles serially related with respect to said live steam jet producing means, with which nozzles said conduit and said auxiliary venturi respectively communicate, said injector including a throttle valve in said water supply conduit interior to the point of communication of said auxiliary Venturi entraining means with said conduit having a minimum capacity not less than the capacity of the auxiliary Venturi entraining means, whereby variations in the 25 volume of water admitted by said throttle valve affect the volume of water supplied direct to said main venturi by said conduit without disturbing the constant conditions of flow, temperature and pressure of water supplied by said auxiliary venturi.

30 5. Steam injector as claimed in claim 1, the entraining means of said main venturi comprising a pair of entraining nozzles serially related with respect to said live steam jet producing means, with which nozzles said conduit and said auxiliary venturi respectively communicate, said injector including a throttle valve in said water supply conduit interior to the point of communication of said auxiliary Venturi entraining means with said conduit having a minimum capacity not less than the capacity of the auxiliary Venturi entraining means, whereby variations in the 35 volume of water admitted by said throttle valve affect the volume of water supplied direct to said main venturi by said conduit without disturbing the constant conditions of flow, temperature and pressure of water supplied by said auxiliary venturi.

40 6. Steam injector as claimed in claim 1, the entraining means of said main venturi comprising a pair of entraining nozzles serially related with respect to said live steam jet producing means, with which nozzles said conduit and said auxiliary venturi respectively communicate, said injector including a throttle valve in said water supply conduit interior to the point of communication of said auxiliary Venturi entraining means with said conduit having a minimum capacity not less than the capacity of the auxiliary Venturi entraining means, whereby variations in the 45 volume of water admitted by said throttle valve affect the volume of water supplied direct to said main venturi by said conduit without disturbing the constant conditions of flow, temperature and pressure of water supplied by said auxiliary venturi.

7. Steam injector, a main venturi, a forcing nozzle and a pair of serially related water entraining nozzles adjacent the anterior end of said main venturi, and a valve controlled live steam inlet communicating with said forcing and entraining nozzles, means forming separate water entraining chambers surrounding the mouths of said entraining nozzles and in communication therewith, a auxiliary venturi having a pressure building nozzle communicating with one of said entraining chambers, a forcing and an entraining nozzle for said auxiliary venturi, means for admitting exhaust steam to said forcing and entraining nozzles, means forming a chamber surrounding said auxiliary venturi in communication with the other entraining chamber, a conduit communicating with a water supply for conducting a body of water sequentially past the mouth of the entraining nozzle of said auxiliary venturi to said surrounding chamber, whereby when exhaust steam is operating said auxiliary venturi, water to the capacity of said entraining nozzle is diverted into said auxiliary venturi from said water body and delivered heated and under pressure to the associated entraining nozzle of said main venturi, excess water flowing by way of said surrounding chamber to the other entraining nozzle of said main venturi.

8. Steam injector, a main venturi, a forcing nozzle and a pair of serially related water entraining nozzles adjacent the anterior end of said main venturi, and a valve controlled live steam inlet communicating with said forcing and entraining nozzles, means forming separate water entraining chambers surrounding the mouths of said entraining nozzles and in communication therewith, a auxiliary venturi having a pressure building nozzle communicating with one of said entraining chambers, a forcing and an entraining nozzle for said auxiliary venturi, means for admitting exhaust steam to said forcing and entraining nozzles, means forming a chamber surrounding said auxiliary venturi in communication with the other entraining chamber, a conduit communicating with a water supply for conducting a body of water sequentially past the mouth of the entraining nozzle of said auxiliary venturi to said surrounding chamber, whereby when exhaust steam is operating said auxiliary venturi, water to the capacity of said entraining nozzle is diverted into said auxiliary venturi from said water body and delivered heated and under pressure to the associated entraining nozzle of said main venturi, excess water flowing by way of said surrounding chamber to the other entraining nozzle of said main venturi.

9. Steam injector, a main venturi, a forcing nozzle and a pair of serially related water entraining nozzles adjacent the anterior end of said main venturi, and a valve controlled live steam inlet communicating with said forcing and entraining nozzles, means forming separate water entraining chambers surrounding the mouths of said entraining nozzles and in communication therewith, a auxiliary venturi having a pressure building nozzle communicating with one of said entraining chambers, a forcing and an entraining nozzle for said auxiliary venturi, means for admitting exhaust steam to said forcing and entraining nozzles, means forming a chamber surrounding said auxiliary venturi in communication with the other entraining chamber, a conduit communicating with a water supply for conducting a body of water sequentially past the mouth of the entraining nozzle of said auxiliary venturi to said surrounding chamber, whereby when exhaust steam is operating said auxiliary venturi, water to the capacity of said entraining nozzle is diverted into said auxiliary venturi from said water body and delivered heated and under pressure to the associated entraining nozzle of said main venturi, excess water flowing by way of said surrounding chamber to the other entraining nozzle of said main venturi.

10 10. Steam injector, a main venturi, a forcing nozzle and a pair of serially related water entraining nozzles adjacent the anterior end of said main venturi, and a valve controlled live steam inlet communicating with said forcing and entraining nozzles, means forming separate water entraining chambers surrounding the mouths of said entraining nozzles and in communication therewith, a auxiliary venturi having a pressure building nozzle communicating with one of said entraining chambers, a forcing and an entraining nozzle for said auxiliary venturi, means for admitting exhaust steam to said forcing and entraining nozzles, means forming a chamber surrounding said auxiliary venturi in communication with the other entraining chamber, a conduit communicating with a water supply for conducting a body of water sequentially past the mouth of the entraining nozzle of said auxiliary venturi to said surrounding chamber, whereby when exhaust steam is operating said auxiliary venturi, water to the capacity of said entraining nozzle is diverted into said auxiliary venturi from said water body and delivered heated and under pressure to the associated entraining nozzle of said main venturi, excess water flowing by way of said surrounding chamber to the other entraining nozzle of said main venturi.

11 11. Steam injector, a main venturi, a forcing nozzle and a pair of serially related water entraining nozzles adjacent the anterior end of said main venturi, and a valve controlled live steam inlet communicating with said forcing and entraining nozzles, means forming separate water entraining chambers surrounding the mouths of said entraining nozzles and in communication therewith, a auxiliary venturi having a pressure building nozzle communicating with one of said entraining chambers, a forcing and an entraining nozzle for said auxiliary venturi, means for admitting exhaust steam to said forcing and entraining nozzles, means forming a chamber surrounding said auxiliary venturi in communication with the other entraining chamber, a conduit communicating with a water supply for conducting a body of water sequentially past the mouth of the entraining nozzle of said auxiliary venturi to said surrounding chamber, whereby when exhaust steam is operating said auxiliary venturi, water to the capacity of said entraining nozzle is diverted into said auxiliary venturi from said water body and delivered heated and under pressure to the associated entraining nozzle of said main venturi, excess water flowing by way of said surrounding chamber to the other entraining nozzle of said main venturi.

12 12. Steam injector, a main venturi, a forcing nozzle and a pair of serially related water entraining nozzles adjacent the anterior end of said main venturi, and a valve controlled live steam inlet communicating with said forcing and entraining nozzles, means forming separate water entraining chambers surrounding the mouths of said entraining nozzles and in communication therewith, a auxiliary venturi having a pressure building nozzle communicating with one of said entraining chambers, a forcing and an entraining nozzle for said auxiliary venturi, means for admitting exhaust steam to said forcing and entraining nozzles, means forming a chamber surrounding said auxiliary venturi in communication with the other entraining chamber, a conduit communicating with a water supply for conducting a body of water sequentially past the mouth of the entraining nozzle of said auxiliary venturi to said surrounding chamber, whereby when exhaust steam is operating said auxiliary venturi, water to the capacity of said entraining nozzle is diverted into said auxiliary venturi from said water body and delivered heated and under pressure to the associated entraining nozzle of said main venturi, excess water flowing by way of said surrounding chamber to the other entraining nozzle of said main venturi.

training nozzles adjacent the anterior end of said main venturi, and a valve controlled live steam inlet communicating with said forcing and entraining nozzles, means forming separate water entraining chambers surrounding the mouths of said entraining nozzles and in communication therewith, an auxiliary venturi having a pressure building nozzle communicating with one of said entraining chambers, a forcing and an entraining nozzle for said auxiliary venturi, means for admitting exhaust steam to said forcing and entraining nozzles, means forming a water passage from a water supply to the mouth of the entraining nozzle of said auxiliary venturi, a throttle valve in said water passage for varying the volume of water delivered to said water passage, said valve permitting a minimum flow equal at least to the capacity of the entraining nozzle of said auxiliary venturi when working under exhaust steam pressure, the capacity of said nozzle being negligibly small when no exhaust steam is present, and a by-pass about said auxiliary venturi for conducting water in excess of that diverted through said auxiliary venturi to the other entraining nozzle of said main venturi whereby within the throttling limits of said valve said auxiliary venturi under a given head of exhaust steam delivers a constant volume of water at constant temperature and pressure to said main venturi.

6. In a steam injector as claimed in claim 4, a casing about the velocity building portion of said main venturi forming an overflow chamber, spillways from said main venturi to said overflow chamber, a fluid pressure closed relief valve for said overflow chamber and a connection from the entraining chamber with which said auxiliary venturi communicates, to a closing means for said relief valve, whereby when said auxiliary venturi is assisting the operation of said injector said relief valve is held closed.

7. In a steam injector, a main venturi, a forcing nozzle and a pair of serially related water entraining nozzles adjacent the anterior end of said main venturi and a valve controlled live steam inlet communicating with said forcing and entraining nozzles, means for supplying water to said main venturi comprising a conduit defining an ante-chamber from which two lateral branches debouch, a valve for admitting water to said ante-chamber from a water supply, said branches respectively communicating with said entraining nozzles, one branch being an exhaust steam venturi having an entraining nozzle the mouth of which communicates with said ante-chamber, the other branch being a chamber surrounding said exhaust steam venturi beyond the mouth of said entraining nozzle, said ante-chamber communicating with said surrounding chamber above the level of the mouth of said exhaust steam entraining nozzle whereby the mouth of said entraining nozzle is first inundated by water supplied to said ante-chamber, the excess then overflowing into said outer chamber and to the associated entraining nozzle of the main venturi.

8. In a steam injector, a main venturi, a forcing nozzle and a pair of serially related water entraining nozzles adjacent the anterior end of said main venturi and a valve-controlled live steam inlet communicating with said forcing and entraining nozzles, means for supplying water to said main venturi comprising a conduit defining an ante-chamber from which two lateral branches

debouch, a valve for admitting water to said ante-chamber from a water supply, said branches respectively communicating with said entraining nozzles, one branch being an exhaust steam venturi having an entraining nozzle the mouth of which communicates with said ante-chamber, the other branch being a chamber surrounding said exhaust steam venturi beyond the mouth of said entraining nozzle, the latter having spillways communicating with said surrounding chamber, said ante-chamber communicating with said surrounding chamber above the level of the mouth of said exhaust steam entraining nozzle whereby the mouth of said entraining nozzle is first inundated by water supplied to said ante-chamber, the excess then overflowing into said outer chamber and to the associated entraining nozzle of the main venturi.

9. Steam injector comprising a main venturi, a forcing nozzle and a pair of water entraining nozzles adjacent the anterior end of said main venturi, means forming separate water entraining chambers surrounding the mouths of said entraining nozzles and in communication therewith, an auxiliary venturi having its pressure building nozzle communicating with one of said entraining chambers, a forcing and an entraining nozzle for said auxiliary venturi, a valve controlling communication with a source of exhaust steam for admitting exhaust steam to the forcing and entraining nozzle of said auxiliary venturi, a hollow fitting through which said auxiliary venturi extends defining a conduit communicating with the mouth of the entraining nozzle of said auxiliary venturi and defining a chamber surrounding said auxiliary venturi beyond the mouth of said entraining nozzle, communicating on the one hand with said conduit above the level of the mouth of said entraining nozzle, and on the other

hand with the other entraining nozzle of the main venturi, said fitting defining a valve chamber communicating with a water supply and with said conduit by way of a valve port, a live steam valve controlling the admission of live steam to the forcing and entraining nozzles of said main venturi, a water valve controlling said valve port, said water valve carrying a disk in spaced relation thereto, smaller than said valve port and having a throttling function in cooperation with said valve port, a common connection between said live steam valve and said water valve including an operating lever, such that by a single movement of said lever in starting said injector, said valves open together, the water valve at a faster rate than said live steam valve, and reach their full open areas before they reach their limits of movement in an opening direction so that they have a range of movement within their full open capacity phase, the disk of the water valve passing through said valve port within the full open capacity phase of said water valve, so quickly that its throttling effect is negligible, and occupying said valve chamber when at the limit of opening movement of said water valve, and while in said valve chamber, movable towards and from said valve port responsive to movements of said lever for throttling the volume of water supplied to said conduit.

10. Steam injector as claimed in claim 9, said exhaust steam valve being opened by exhaust steam pressure, and said common connection between said live steam valve and water valve including a stop interposed in the path of opening movement of the exhaust steam valve when said

live steam valve and water valve are closed to prevent opening of said exhaust steam valve when said injector is not operating.

11. Steam injector comprising a main venturi having live steam jet producing means at its anterior end and water entraining means operatively related to said live steam jet producing means, a conduit from a water supply to said entraining means including an exhaust steam venturi entraining water from said conduit and heating it and delivering it under some pressure to the entraining means of said main venturi, an inlet from a source of exhaust steam, a normally closed valve controlling the admission of exhaust steam from said inlet to said exhaust steam venturi, exhaust steam operated means for opening said valve, and means for transmitting exhaust steam pressure from said inlet to said valve opening means, the capacity of said inlet to deliver steam being greater than the capacity of said exhaust steam venturi to receive steam whereby a dominant exhaust steam pressure is maintained in said inlet, holding said valve open while ever said exhaust steam venturi is in operation.

12. Steam injector comprising a main venturi having live steam jet producing means at its anterior end and water entraining means operatively related to said steam jet producing means, a conduit from a water supply to said entraining means including an exhaust steam venturi having forcing and entraining nozzles, the latter entraining water from said conduit, an inlet from a source of exhaust steam, an inlet closed valve controlling the admission of exhaust steam from said inlet to the forcing and entraining nozzles of said exhaust steam venturi, exhaust steam operated means for opening said valve, means for transmitting exhaust steam pressure from said inlet to said valve opening means, the cross-sectional area of said inlet being greater than the cross-sectional areas of said forcing and entraining nozzles whereby a dominant exhaust steam pressure is maintained in said inlet, holding said valve open while ever said exhaust steam venturi is in operation.

13. In a steam injector, a main venturi, a forcing nozzle and a pair of serially related water entraining nozzles adjacent the anterior end of said main venturi and a valve controlled live steam inlet communicating with said forcing and entraining nozzles, means for supplying water to said main venturi comprising a conduit defining an ante-chamber from which two lateral branches debouch, a valve for admitting water to said ante-chamber from a water supply, said branches respectively communicating with said entraining nozzles, one branch being an exhaust steam venturi having an entraining nozzle the mouth of which communicates with said ante-chamber, the other branch being a chamber surrounding said exhaust steam venturi beyond the mouth of said entraining nozzle, the latter having spillways communicating with said surrounding chamber, said ante-chamber communicating with said surrounding chamber above the level of the mouth of said exhaust steam entraining nozzle whereby the mouth of said entraining nozzle is first inundated by water supplied to said ante-chamber, the excess then overflowing into said outer chamber and to the associated entraining nozzle of the main venturi, means forming an overflow chamber for said exhaust steam venturi excluding said conduit, with which other spillways from said exhaust steam venturi communicated, and a relief valve for said overflow chamber.

14. In a steam injector, a main venturi, a forcing nozzle and a pair of serially related water entraining nozzles adjacent the anterior end of said main venturi and a valve controlled live steam inlet communicating with said forcing and entraining nozzles, means for supplying water to said main venturi comprising a conduit defining an ante-chamber from which two lateral branches debouch, a valve for admitting water to said ante-chamber from a water supply, said branches respectively communicating with said entraining nozzles, one branch being an exhaust steam venturi having an entraining nozzle the mouth of which communicates with said ante-chamber, the other branch being a chamber surrounding said exhaust steam venturi beyond the mouth of said entraining nozzle, the mouth of which communicates with said ante-chamber, the other branch being a chamber surrounding said exhaust steam venturi beyond the mouth of said exhaust steam entraining nozzle, said ante-chamber communicating with said surrounding chamber above the level of the mouth of said exhaust steam entraining nozzle whereby the mouth of said exhaust steam entraining nozzle is first inundated by water supplied to said ante-chamber, the excess overflowing into said surrounding chamber and to the associated entraining nozzle of the main venturi.

15. In a steam injector, a main venturi, a forcing nozzle and a pair of serially related water entraining nozzles adjacent the anterior end of said main venturi and a valve controlled live steam inlet communicating with said forcing and entraining nozzles, means for supplying water to said main venturi comprising a conduit defining an ante-chamber having an upstanding wall, a valve for admitting water to said ante-chamber from a water supply, said ante-chamber being divided into two lateral branches respectively communicating with the entraining nozzles of said main venturi, one branch being an exhaust steam venturi passing through said upstanding wall having an exhaust steam entraining nozzle communicating with said ante-chamber, the other branch being a chamber surrounding said exhaust steam venturi beyond the mouth of said exhaust steam entraining nozzle, said ante-chamber communicating with said surrounding chamber through said upstanding wall above said exhaust steam entraining nozzle whereby the mouth of said exhaust steam entraining nozzle is first inundated by water supply to said ante-chamber, the excess overflow into said surrounding chamber upon the outer surface of said exhaust steam venturi within said surrounding chamber, and to the associated entraining nozzle of the main venturi.

16. In a steam jet pump of the kind having a tube assembly and a live steam forcer nozzle arranged to deliver steam into the entrance end of said tube assembly, a pair of serially arranged entraining nozzles arranged to deliver fluid into the entrance end of said tube assembly, means providing a water inlet chamber, separate conduits leading from said chamber to the respective entraining nozzles, one of said conduits comprising a tube assembly provided with lateral spillways opening into the other conduit, and means for delivering a jet of exhaust steam into said latter tube assembly.

17. In a steam jet pump of the kind having a tube assembly and a live steam forcer nozzle arranged to deliver steam into the entrance end of

said tube assembly, a pair of serially arranged water-entraining nozzles arranged to deliver fluid into the entrance end of said tube assembly, means providing a water inlet chamber, separate conduits leading from said chamber to the respective entraining nozzles, one of said conduits comprising a tube assembly provided with lateral spill-

ways opening into the other conduit, said last named tube assembly being arranged to receive water at a lower level from said water inlet chamber than the other conduit, and means for delivering a jet of exhaust steam into said last named tube assembly.

WALTER HOWARD TINKER.
